UNITED STATES PATENT OFFICE.

EMORY S. LEWIS, OF BROOKLYN, NEW YORK.

DESIGN FOR A LIGHTING-FIXTURE BAND.

Application filed July 28, 1924. Serial No. 10,275. Term of patent 7 years.

To all whom it may concern:

Be it known that I, EMORY S. LEWIS, a citizen of the United States, and a resident of the city of New York, county of Kings, and State of New York, have invented a new, original, and ornamental Design for Lighting-Fixture Bands, of which the following is a specification, reference being had to the accompanying drawing, forming a part hereof.

In these drawings:

Fig. 1 is an elevational view of the lighting fixture band, and

Fig. 2 is a sectional view of the lighting fixture band.

I claim:

The ornamental design for a lighting fixture band substantially as shown.

EMORY S. LEWIS.
